(57) **CLAIM**

The ornamental design for our ratchet gear having elliptical drive hole, as shown and described.

DESCRIPTION

FIG. 1 is a perspective view of our design for a ratchet gear having elliptical drive hole;

FIG. 2 is a top plan view of the ratchet gear having elliptical drive hole of FIG. 1;

FIG. 3 is a bottom plan view of the ratchet gear having elliptical drive hole of FIG. 1;

FIG. 4 is a front elevation view of the ratchet gear having elliptical drive hole of FIG. 1;

FIG. 5 is a rear elevation view of the ratchet gear having elliptical drive hole of FIG. 1; and

FIG. 6 is a right side elevation view of the ratchet gear having elliptical drive hole of FIG. 1; and,
FIG. 7 is a left side elevation view of the ratchet gear having elliptical drive hole of FIG. 1.
